UNITED STATES PATENT OFFICE

ERWIN E. THURSTON, OF ROCHESTER, NEW YORK, ASSIGNOR TO UNITED STATES HOFFMAN MACHINERY CORPORATION, OF NEW YORK, N. Y., A CORPORATION OF DELAWARE

GARMENT-PRESSING MACHINE

Application filed February 24, 1925. Serial No. 11,115.

The present invention relates to garment pressing machines and more particularly to the type having a pressing element provided with a large steam chamber and a small steam chamber having a valved communication with the large steam chamber to receive steam therefrom, said small steam chamber being arranged within the large steam chamber and provided with openings through which the 5 pressing surface of the pressing element whereby the goods being pressed may be steamed. An object of this invention is to mount all the movable parts and parts subject to wear of the controlling valve between 10 the steam chambers so that they may be readily reached for repair or replacement from the exterior of the two chambers. 15

To these and other ends, the invention consists of certain parts and combinations of 20 parts, all of which will be hereinafter described; the novel features being pointed out in the appended claims.

In the drawings:

Fig. 1 is a vertical section through the 25 pressing element with the present invention associated therewith;

Fig. 2 is an enlarged section through the valve; and

Fig. 3 is a plan view of the valve.

Referring more particularly to the illustrated embodiment of the invention, 1 indicates the pressing element, 2 indicates the enlarged chamber formed above said pressing element and receiving steam from a steam 30 supply pipe 3. Arranged within the chamber 2 is a small chamber 4 separated from the chamber 2 by a partition 5. The pressing element 1 has openings 6 extending through its pressing surface and communicating with the interior of the chamber 4.

The feature of this invention is the provision of a means which will permit a valve arranged exteriorly of the chambers 2 and 4 to control the flow of steam from the chamber 2 to the chamber 4. In this instance, a valve casing 9 is formed with two chambers 8 and 11, separated by a partition 19 formed with an opening 10. The chamber 8 connects with the chamber 2 by a passageway 7 and the chamber 11 connects with the

chamber 4 by a passageway 12. Preferably the two passageways 7 and 12 are formed in a cylindrical extension 13 on the valve casing 9, this extension 13 having its lower end screw threaded and engaged with the screw 55 threaded walls of an opening 14 formed in the top of the chamber 4. This cylindrical extension also extends through an opening 15 in the top of a chamber 2 and is externally threaded at 16 for engagement by a nut 17 60 which presses a packing 18 firmly against the top of the chamber 2 about the opening 15 to prevent the escape of steam at the joint between the chamber wall and the cylindrical extension. 65

The partition 19 in the valve housing on one side is provided with a seat 20 for a valve member 21 which by a helical spring 22 is pressed toward the seat 20. This spring surrounds the stem 23 of the valve member and abuts the rear face of the valve, its other end being in abutment with an internal shoulder 24 with a plug or cap 25 which closes an opening in the casing 9 through which when the cap or plug is removed, the valve 21 may be passed. When the plug is removed the seat 20 will be exposed for reseating. 70 75

Movement of the valve 21 away from its seat may be effected in any suitable manner. In this instance, a plunger 26 is guided longitudinally in a bushing 27 removably fitted in the valve casing and carrying a packing gland 28. One end of this plunger engages a socket 29 projected from the valve 21 while the other end is engaged by a U shaped member or yoke 30, the arms of which are pivotally connected at 31 to lugs 32 extending downwardly from a lever 33 which is pivoted at 34 to a bracket arm 35 on the valve casing 9. 80 85

Depression of the lever 33 forces the plunger 26 inwardly to displace the valve 21 from its seat 20 against the action of its spring 22 and, upon the release of the lever 33, the valve 21 reengages the seat 20 to close the opening 10 between the two chambers 8 and 11. Of course, when the opening 10 is opened, steam will pass from the chamber 2 to the chamber 4 and out through the ports 6 to supply steam to the material being pressed, and, when the 90 95 100

opening 10 is closed by the valve 21, the steam will be confined to the chamber 2.

From the foregoing it will be seen that there has been provided in a pressing element having two chambers, one of which is arranged within the other and has ports leading therefrom through the pressing surface of the pressing element, a valve casing arranged exteriorly of said chamber and having an extension provided with two passageways, one of which connects the valve casing with one chamber and the other of which connects the valve casing with the other chamber, a valve being arranged in the valve casing exteriorly of both chambers to control the flow of one passageway to the other. By this arrangement the movable valve parts are arranged to be reached exteriorly of both of the steam chambers without removing the valve casing. Furthermore, it is possible to utilize the steam pressure in the chamber 2 for maintaining the valve member closed and, as a consequence, a much lighter spring may be employed for giving the valve a tendency to move to closed position. As a result the amount of pressure required to open the valve is reduced to a minimum. This arrangement makes it possible to repair a pressing element of the type herein mentioned in a very short space of time, thus reducing the loss through the occasion of the non-use of the pressing machine.

What I claim as my invention and desire to secure by Letters Patent is:

1. The combination with a pressing element having two steam chambers, one of which is arranged above the other, said chambers having a common wall separating them, of a member connecting the top wall of the upper chamber and said common wall and provided with two passageways, one of which leads from the lower chamber upwardly through said member and the other of which leads from the upper chamber upwardly through said member, means providing communication between said passageways above said upper chamber, and a valve member controlling said communication.

2. The combination with a pressing element having two steam chambers, one of which is arranged above the other, and said chambers being separated by a common wall, the top of the upper chamber and the common separating wall having aligned openings, of a member extending through said openings and having a steam tight connection with the common wall and the top wall of the upper chamber, said member having two passageways, one of which leads through the lower end of the member upwardly and the other of which leads through the side of said member and in an upward direction, means arranged above the upper chamber and providing communication between said passageways above said upper chamber, and a valve member controlling said communication.

3. The combination with a pressing element having two steam chambers, one of which is arranged above the other, and said chambers being separated by a common wall, the top of the upper chamber and the common separating wall having aligned openings, a member extending through said openings and having a steam tight connection with the common wall and the top wall of the upper chamber, said member having two passageways, one of which leads through the lower end of the member upwardly and the other of which leads through the side of said member and in an upward direction, means arranged above the upper chamber and providing communication between the two passageways, and a valve member arranged to control such communication.

4. The combination with a pressing element having two steam chambers arranged one above the other with a common wall between them, said common wall being provided with an opening and the top of the upper chamber being provided with an opening aligned with the opening in the common wall, the opening in the common wall having its walls internally threaded, a member extending through the upper chamber having its lower end externally threaded for engagement with the threaded walls of the opening in the common wall and provided with two passageways, one of which leads upwardly through the member from the lower chamber, and the other of which extends laterally through the member between the common wall and the top wall of the upper chamber and leads upwardly, means providing communication between said passageways above the upper wall of the upper chamber, a valve for controlling such communication, and means providing a steam tight joint about the member at the point where it passes through the upper wall of the upper chamber.

5. The combination of a pressing element having two steam chambers, one of which is arranged above the other, a common wall being provided between the chambers, the top of the common wall being provided with an opening, the walls of which are screw threaded, and the top of the upper chamber having an opening aligned with the opening in the common wall, a cylindrical member extending through the upper chamber having its lower end threaded for engagement with the screw threaded walls of the opening in the common wall and being provided above the upper wall of the upper chamber with screw threads, said cylindrical member having two passageways, one extending from the lower chamber upwardly through the member to a point above the upper wall, and the other extending through the side of the member between the two screw threaded portions upwardly beyond the upper screw threaded portion, a packing ring arranged on the upper

5 screw threaded portion for cooperation with the upper wall of the upper chamber, means providing communication between the upper ends of the passageways above the upper chamber, and a valve arranged to control the communication between said passageways.

10 6. The combination with a valve casing, of a cylindrical member extending from one side of the valve casing and having its outer end provided with screw threads, and its portion adjacent the valve casing provided with screw threads, said member also having two passageways, one of which leads through the outer end of the member to the valve casing, and the other of which leads through the side of the member between the two screw threaded portions to the valve casing, and a valve member arranged in the valve casing to control communication between the two 20 passageways.

25 7. The combination with a valve casing having two chambers and a partition separating said chambers and provided with an opening, and a valve for closing the opening between said chambers, of a cylindrical extension projected from one side of the casing and formed with external screw threads adjacent its outer end and also adjacent its inner end, said extension having two passageways, one of which leads through the side of the cylindrical extension between the two screw threaded portions and connects with one of the chambers of the valve casing and the other of which connects with the other chamber of 30 the valve casing and leads through the free end of the cylindrical extension and a packing nut arranged to operate on the screw threaded portion adjacent the inner end of the extension.

35 8. The combination with a cylindrical member having an external screw thread adjacent one end thereof and an external screw thread adjacent the opposite end thereof, of means providing a chamber adjacent the upper end of the cylindrical member, said member having two passageways, one leading to the chamber from that end of the cylindrical member opposite the chamber and the other leading to the chamber from a point between the two screw threaded portions and below the said chamber, and means arranged in the chamber for controlling connection between the two passageways.

40 9. In a valve, the combination with a cylindrical member having an externally threaded portion at one end and having two passageways, one leading through the threaded end, and the other leading through the side of the cylindrical member above the threaded portion, of means forming a chamber adjacent the other end of said member communicating with both passageways, the bottom of said chamber being above the lower portions of both passageways, means arranged in the chamber for controlling the

flow from one passageway to the other, and joint forming means arranged about said cylindrical member above the lower ends of both passageways for cooperation with a suitable element with which the valve may be associated.

45 10. The combination with a pressing element having two steam chambers, one of which is arranged above the other, said chambers having a common wall separating them, of a member connecting the top wall of the upper chamber and said common wall and provided with two passageways, one of which leads from the lower chamber upwardly through said member and the other of which leads from the upper chamber, means providing communication between both of said passageways, a valve seat arranged in said communicating means above the lower ends of both passageways, and a valve member for 50 cooperating with the seat to control the communication.
